W. S. GRAFFAM

CRAMPING DEVICE

Filed Aug. 7, 1923

Walter S. Graffam
INVENTOR.

UNITED STATES PATENT OFFICE.

WALTER S. GRAFFAM, OF SHREWSBURY, MASSACHUSETTS.

CRAMPING DEVICE.

Application filed August 7, 1923. Serial No. 656,256.

To all whom it may concern:

Be it known that I, WALTER S. GRAFFAM, a citizen of the United States, residing at Shrewsbury, in the county of Worcester and State of Massachusetts, have invented new and useful Improvements in Cramping Devices, of which the following is a specification.

My invention relates to improvements in mechanical cramping or clamping devices, for holding articles together by means of screw pressure.

The principal objects of the invention are, first, to provide a cramp, the frame of which can be made of a single piece pressed sheet metal, so formed as to give it maximum strength combined with lightness; and, second, to so construct it that it can be manufactured cheaply.

I attain these objects by the mechanism illustrated in the accompanying drawing, in which:—

Fig. 1 is a plan view of the assembled cramp;

Fig. 2 is a bottom view;

Fig. 3 is a section on the line A—A;

Fig. 4 is a section through the center on the line B—B.

Similar numerals refer to similar parts throughout the several views.

The frame 1 is made of a single piece of sheet metal, cut or stamped out to the desired shape, folded back upon itself, and having flanges 2 drawn outwardly along the three sides of a central opening. When the metal is folded back upon itself it is so formed as to leave two cylindrical openings into one of which the anvil 3 is inserted, the second one being threaded to receive the screw 4.

The frame 1 is fastened firmly together by means of rivets 5, or by other commonly used methods such as welding, brazing or soldering.

The anvil 3 has a shank 6 which is forced

into one of the cylindrical openings of the frame 1, or headed over on the bottom end as an ordinary rivet.

The screw 4, has a formed head 7, which may be knurled or flattened to any shape desirable.

The formed washer 8, has a cupped shaped hole through the center into which the reduced end 9, of the screw 4 is inserted and lightly headed over to prevent the washer 55 8 from dropping off, while permitting it to rotate freely.

I am aware that prior to my invention, C cramps have been made in many ways, so I do not claim the fundamental principle of 60 this kind of a holding or cramping device.

Although I have illustrated and described only a single embodiment of the invention, I am aware of the fact that many modifications can be made therein by any person 65 skilled in the art without departing from the scope of the invention as expressed in the claims.

Therefore, I do not wish to be limited to all the details of construction herein shown 70 and described, but what I do claim is:

In a cramping device shaped like the letter C, the combination of a frame made from a single piece of sheet metal, with a central opening having flanges drawn up 75 around the sides of said central opening; the metal folded back upon itself so as to leave two cylindrical shaped openings the axes of which lie in the same straight line; the two halves of the folded metal held together as 80 one piece by rivets or other commonly used methods; an anvil inserted into one of the cylindrical shaped openings; a screw threaded into the other of said cylindrical openings; a cupped washer attached loosely to 85 the end of said screw; all substantially as described and set forth.

In testimony whereof I have hereunto affixed my signature.

WALTER S. GRAFFAM.
